UNITED STATES PATENT OFFICE.

CLIFFORD COUNCIL, OF WILLIAMSVILLE, ILLINOIS.

DESIGN FOR A BODY MEMBER FOR A PLATE-LIFTER.

SPECIFICATION forming part of Design No. 33,146, dated August 28, 1900.

Application filed June 26, 1900. Serial No. 21,688. Term of patent 7 years.

To all whom it may concern:

Be it known that I, CLIFFORD COUNCIL, a citizen of the United States, residing at Williamsville, in the county of Sangamon and State of Illinois, have invented and produced a new, original, and useful Design for a Body Member for Plate-Lifters, of which the following is a specification, reference being had to the accompanying drawings, forming part of this application.

In the drawings, Figure 1 is a top plan of a plate-lifter embodying my invention. Fig. 2 is a side elevation of same, and Fig. 3 is an enlarged vertical transverse section on the line X X of Fig. 1.

Similar reference-numerals designate like parts in all of the views.

My design relates to plate-lifters.

My said design resides and is embodied in a body member for plate-lifters of the form and configuration set forth as a definite article of manufacture.

My said design embraces a body member for plate-lifters formed of a single piece of wire bent and twisted to form a handle 1,

rails 2, arms 3, and hooks 4 on said arms. The rails 2 and the arms 3 are twisted together and form a stay 6 at the juncture of the arms with the rails. The rails 2 and the side parts of the handle 1 are twisted together 30 and form a stay 5 at the juncture of the handle with the rails. Each of the arms 3 is bent at approximately a right angle, so as to form a horizontal member and a vertical member, as shown. At the lower extremity of 35 each arm is a hook 4, which is perpendicular to the vertical member of the arm and projects inwardly parallel to the rails 2.

That which I have invented and produced, and desire to secure by Letters Patent, is— 40

The design for a body member of a plate-lifter substantially as shown and described.

In witness whereof I have hereunto subscribed my name, at Springfield, Illinois, this 30th day of May, 1900.

CLIFFORD COUNCIL.

Witnesses:

FRANK HUDSON,
CAREY E. BARNES.
